(57) **CLAIM**

The ornamental design for a nozzle for a debris blower, as shown and described.

DESCRIPTION

FIG. 1 is a right front perspective view of a nozzle for a debris blower showing the new design, the nozzle shown attached to a debris (e.g., leaf) blower;

FIG. 2 is a right front perspective view of the nozzle for a debris blower removed from the debris blower;

FIG. 3 is a right front perspective view of the nozzle for a debris blower with unclaimed subject matter removed;

FIG. 4 is a right rear perspective view thereof;

FIG. 5 is a left rear perspective view thereof;

FIG. 6 is a right side elevational view thereof;

FIG. 7 is a left side elevational view thereof;

FIG. 8 is a top plan view thereof;

FIG. 9 is a bottom plan view thereof;

FIG. 10 is a front elevational view thereof; and,

FIG. 11 is a rear elevational view thereof.

The broken line showing illustrates unclaimed portions of the nozzle for a debris blower, as well as the environment of the claimed design, neither of which forms a part of the claimed design.

1 Claim, 8 Drawing Sheets
